His Attorney

UNITED STATES PATENT OFFICE.

EDWARD JOSEPH GURREN, OF ST. LOUIS, MISSOURI.

COMBUSTION DEVICE.

Application filed August 29, 1923. Serial No. 659,907.

To all whom it may concern:

Be it known that I, EDWARD JOSEPH GURREN, a citizen of the United States, residing in the city of St. Louis, in the State of Missouri, have invented a new and useful Improvement in Combustion Devices, of which the following is a full, clear, and exact specification, reference being had to the accompanying drawings, which form a part thereof.

My invention relates to combustion devices and more particularly to combustion devices adapted to be installed in the combustion chamber of a furnace or boiler to more completely burn the volatile gases incident to combustion therein which ordinarily pass out of the combustion chamber and up the chimney unburned.

Heretofore when a fire was started in the combustion chamber or when a new supply of coal was put therein a great amount of volatile gas was generated which, because of an insufficiency of free oxygen, would pass out of the combustion chamber and up the chimney unburned, thereby causing a great waste of heat since this volatile gas contained a high percentage of heat units. The generation of this volatile gas after the fire has been started in the combustion chamber may be obviated to some extent by feeding the coal therein in small quantities, but this procedure necessitates constant and expert stoking and therefore is not practical in ordinary use.

The objects of my invention are to provide in the combustion chamber of a furnace or boiler a combustion device which will bring about the more complete combustion of the volatile gases which ordinarily pass unburned into the outer air; to provide a combustion device whereby the gases of combustion when the oxygen content is high, are drawn from the combustion chamber into a storage tank from which they are later returned to the combustion chamber to assist in the combustion when the oxygen content in the combustion chamber is low; and to provide a combustion device for installation in the combustion chamber of a furnace or boiler which will permit feeding a comparatively large quantity of coal into said combustion chamber at a single stoking without the loss of heat due to allowing the volatile gases generated to pass up the chimney unburned.

In the drawings my invention is shown ar-

ranged in a simple furnace used for heating a vessel of water placed above the combustion chamber thereof. This simple form of furnace with my new and improved combustion device arranged therein is shown diagrammatically for the sake of convenience; but I do not propose to limit my invention to use with this form of furnace since my device may be successfully installed in furnaces and boilers of any type.

My invention is fully shown in the accompanying drawings wherein similar letters are used to designate similar parts. Fig. 1 is a sectional elevation showing my device installed in a combustion chamber of a furnace and Fig. 2 is a view along the line 2-2 in Fig. 1.

Referring to the figures, the furnace shown is provided with a combustion chamber A having the grate B with the ash pit C therebeneath. The fire door D is arranged to permit feeding of coal into the combustion chamber. The vessel E adapted to be filled with water is positioned above the combustion chamber A, as shown in the figures. The horizontal flue F at the back of the combustion chamber leads into the chimney G. The flow through the flue F may be controlled by the damper H. The opening J is provided to facilitate cleaning the flue H and the chimney G. My combustion device comprises the horizontal flow pipe K and the return pipe L. The flow pipe K is provided with the branches X having the tubes M with the slots N therein extending downwardly at the sides of the combustion chamber A adjacent to the walls thereof. In like manner the return pipe L is provided with the branches O having the tubes P with the perforations R therein extending downwardly adjacent the walls of the combustion chamber. The upper ends of the tubes M and P are maintained in place by means of the pins S as shown in Fig. 1. The flow pipe K, preferably, leads into the upper part of one end of the storage tank T which is arranged outside of the combustion chamber, preferably high above the furnace, and the pipe K is provided with the check valve U which allows the flow of gases only from the combustion chamber to the tank T. The return pipe L is preferably connected to the tank T at the lowest part of the other end thereof, as shown in the drawings, and is provided with the check valve V which allows

the flow of gases in said pipe from the tank T to the combustion chamber. Each of said pipes is provided with a manually operated damper W for controlling the flow of gases therethrough.

The preferred operation of my combustion device is as follows:

The manually operated dampers W in the pipes K and L are closed and fire is made 10 in the combustion chamber A in the ordinary way. When coal is fed into the furnace in comparatively large quantities there is an insufficient supply of oxygen so that smoke is formed and the volatile gases of combustion 15 pass into the chimney unconsumed. The gases of combustion at this time have a low oxygen content. After the fire has burned a short time the smoke usually disappears and the products of combustion passing from 20 the furnace have a high oxygen content. When the smoke has virtually stopped the damper H in the horizontal flue F, which had been previously opened, is closed until it is about in the position shown in Fig. 25 1, and the manually operated damper W in the flow pipe K is opened to allow the gases of combustion with their surplus of oxygen to pass through the flow pipe into the tank T. The gases of combustion are 30 admitted to the flow pipe through the slots N provided in the tubes M of the branches X. In this way the tank T is filled with gases having a comparatively high oxygen content. When a fresh supply of coal is put 35 on the fire the dampers W are adjusted so that there will be a flow of gas having a high oxygen content from the tank into the furnace where there is an insufficient supply of oxygen, and the oxygen from the gases drawn 40 from the tank will aid in the combustion of the volatile gases in the furnace. Ordinarily the dampers W may be set so that the operation of the device will be entirely automatic. The tank T will be filled between 45 firing periods with products of combustion having a high oxygen content, and then when coal is fed into the furnace these gases will be discharged into the furnace where the oxygen contained in them will be intimately 50 mixed and mingled with the volatile gases passing off from the fresh coal and will aid in the combustion of these volatile gases. The circulation of the products of combustion 55 between the tank T and the combustion chamber is brought about by the relative position of these two members, and it will be such as to free the tank of any gases having a low oxygen content which may have passed 60 into the tank during the period of firing, so that at the beginning of firing the tank will be filled with gases having a high oxygen content. These gases are hot and when discharged into the furnace will aid in supporting the combustion therein. I prefer to have 65 the gases with high oxygen content dis-

charged into the combustion chamber through the small perforations shown in the drawings so that there will be a more complete mixing of volatile gases and the gas from the tank.

I do not propose to limit my invention to the exact details of construction shown in the drawings, since it can be readily seen that the shape and size of the flow pipe K and the return pipe L, the branches X and O 75 with the slots N and the perforations R, respectively, therein, and the storage tank T, may be varied within wide limits without deviating from the spirit of my invention.

What I claim as new and desire to secure 80 by Letters Patent, is:

1. In combination with a furnace having a combustion chamber therein, a tank, a flow pipe connecting said combustion chamber and said tank and adapted to cause the gases from said combustion chamber to pass into said tank, and a return pipe connecting 85 said tank and said combustion chamber and adapted to carry said gases from said tank back into said combustion chamber, thereby causing a circulation of gases from said combustion chamber into and through said tank back to said combustion chamber, and means for preventing a circulation of said gases in the reverse direction. 90

2. In combination with a furnace having a combustion chamber therein, a tank, a flow pipe extending from said combustion chamber and entering said tank above the median line thereof, a return pipe extending from 100 said tank below the median line thereof into said combustion chamber, thereby forming a system of circulation causing a circulation of gases from said combustion chamber into and through said tank back to said combustion chamber, and a check valve in said system for preventing a circulation of gases in the reverse direction. 105

3. In combination with a furnace having a combustion chamber therein, a tank, a flow pipe connecting said combustion chamber and said tank and adapted to cause the gases from said combustion chamber to pass into said tank, and a return pipe connecting 110 said tank and said combustion chamber and adapted to carry said gases from said tank back into said combustion chamber, thereby causing the circulation of gases from said combustion chamber into and through said tank back to said combustion chamber, and a check valve in each of said pipes for controlling the flow therethrough. 115

4. The combination with a furnace having a combustion chamber therein, a tank, a flow pipe extending from said combustion chamber and entering one end of said tank, a return pipe extending from the other end of said tank into said combustion chamber, a valve in each of said pipes for controlling 125 the flow therethrough, said flow pipe having 130

- ing a plurality of openings for the admission of the gases of combustion from said combustion chamber and said return pipe having a plurality of openings for the emission of said gases into said combustion chamber, whereby a circulation of said gases is caused from said combustion chamber into and through said tank back into said combustion chamber.
- 19 5. In combination with a furnace having a combustion chamber therein, a tank, a flow pipe extending from said combustion chamber and entering one end of said tank above the median line thereof, a return pipe 15 extending from the other end of said tank below the median line thereof into said combustion chamber, thereby causing a circulation of gases from said combustion chamber into and through said tank back into said combustion chamber, said flow pipe having 20 a plurality of branches within said combustion chamber and adjacent to the walls thereof which branches have slots therein for the admission of gases to said flow pipes, said return pipe having a plurality of 25 branches within said combustion chamber and adjacent the walls thereof which branches are provided with a plurality of perforations therein for the emission of gases from said return pipe, and a check 30 valve and a manually operated valve in each of said pipes.

In witness whereof I have signed my name to this specification.

EDWARD JOSEPH GURREN.
